UNITED STATES PATENT OFFICE.

LOUIS AARON LEBOWICH, OF BOSTON, MASSACHUSETTS.

FILE FOR CARDS AND THE LIKE.

1,123,326.

Specification of Letters Patent.

Patented Jan. 5, 1915.

Application filed March 20, 1914. Serial No. 826,100.

To all whom it may concern:

Be it known that I, LOUIS AARON LEBOWICH, a citizen of the United States, residing at No. 11 Melville avenue, in Boston, in the county of Suffolk and State of Massachusetts, have invented certain new and useful Improvements in Files for Cards and the like, of which the following is a specification.

10 My invention relates to files for cards and the like and it has for its object to improve the construction of the card holding means with which articles of this kind are usually provided.

15 In my improved file the means for holding or supporting the cards or the like consists of a follower slidably mounted upon a rail connected with the frame or base of the file which may be in the form of a box or 20 drawer. On the follower is mounted a locking lever that is preferably pivoted so as to swing up and down in a plane parallel with the cards or the like, and this lever coöperates, either directly or indirectly, with the 25 rail so that when swung into its lowermost position it locks the follower to the rail and when swung into its uppermost position the follower is freed from the rail and can be adjusted lengthwise of the latter. The ad- 30 vantages to this construction are that the follower can be made comparatively thin so that it does not appreciably detract from the capacity of the file, and by arranging the lever to swing in the manner described not 35 only is space economized but said lever may be constructed so that when occupying its unlocked position its upper end can be used as a handle with which to manipulate the follower, while its downward movement, 40 when shifted into its locked position, may be such as to lower its upper end into an out-of-the-way position so that said end does not project materially above the level of the cards or the like.

45 Other features of my invention are hereinafter pointed out.

In the accompanying drawings: Figure 1 is a longitudinal sectional view of a file constructed in accordance with my invention. 50 Fig. 2 is a section on a larger scale taken on the line 2—2 of Fig. 1. Fig. 3 is a section on line 3—3 of Fig. 2. Fig. 4 is a section on line 4—4 of Fig. 2. Figs. 5 and 6 are, respectively, face and side views of the spring locking plate hereinafter described.

Having reference to the drawings, 1 rep-

resents a box shaped container which may be one of the drawers of a cabinet. The bottom or base 2 of container 1 is made upon its top inner side with a longitudinal groove 60 3 within which is arranged a rectangular or round metal rail 4 on which is slidably mounted a follower 5. The rail 4 may be fastened at its ends to the end walls 6, 6 of container 1 by screws or the like. 65

The follower 5 comprises a body made from a single piece of sheet metal folded upon itself at its top so as to form two vertical parallel walls 7 and 8, the wall 7 being bent laterally at its lower end so as to provide a base 9 which seats upon the top of rail 4. The base 9 is provided at one end with a downwardly extending tongue 10 formed with a rectangular aperture 11 through which the rail 4 extends, while the lower end 70 of wall 8 projects below the rail and is provided with a rectangular aperture 112 through which said rail 4 also extends. In this way the follower is slidably mounted upon the rail so that it cannot become detached while in use and cannot swing side- 75 wise on said rail.

Between the two walls 7 and 8 is arranged a spring clutch plate 12 bearing near its lower edge upon the rail 4 and having its 80 upper edge coöperatively arranged with relation to the cam shaped hub 13 of a clutch operating lever 14 also arranged between the two walls 7 and 8 and pivotally connected therewith by means of a rivet 15. The folded top edges of the walls 7 and 8 are cut away as at 16, Fig. 2, to make a slot 17 at the top of the two walls through which the free end of lever 14 extends to the exterior 85 of the follower so that it is accessible for manipulation. This lever 14 is a thin metal bar and does not add materially to the thickness of the follower. 90

The wall 7 is provided at its sides with diagonal sockets 18 which embrace the ends 100 of an upwardly extending wire bow or bail 19 whose exposed middle portion and ends give to the follower the desired area or size.

The clutch plate 12 is preferably made from hard spring steel and is cut and bent 105 so as to provide a ledge 20 at its top end that is engaged by the lever 14 and an end-wise yielding tongue 21 at its lower end to rest upon the top of rail 4, said tongue being disposed between two arms 22 which embrace the rail 4. Near their junction with the body of plate 12 the arms 22 curve inwardly 110

as at 222 and these curved portions 222 coöperate with the two upper corners of the rail 4 so that when plate 12 is forced downward by lever 14 the opposed curved edges 222 bite onto said corners and thereby firmly clutch the rail and hold the follower against movement. Near its upper end plate 12 is made with a vertical slot 23 into which projects a lug 24 bent inwardly from the wall 7. The engagement of the arms 22 with rail 4 and the engagement of the lug 24 with the slot 23 maintain the clutch plate 12 in position with provision for limited movement toward and from said rail.

When lever 14 occupies the position shown in full lines in Fig. 2 the tongue 21 of clutch plate 12 supports the latter so that the curved parts 222 are out of locking engagement with rail 4 and the follower is free to be shifted on the latter, but when lever 14 is swung down into the position shown by dotted lines in said figure, the cam portion 13 thereof forces plate 12 downward against the yielding resistance of spring tongue 21 causing the portions 222 to grip the upper corners of the rail and lock the follower against movement on the rail. The tongue 21 is offset slightly from the body of plate 12 as shown at 25 so that said plate will be yielding under the pressure of lever 14.

As will be clear the lever 14 normally occupies a depressed position where it is out of the way and when swung upwardly in a plane crosswise of the rail 4 to unlock the follower, the free end of the lever is brought into a position above the latter and the contents of the file so that it can be used as a handle by means of which to shift the follower on the rail. Also, by arranging the lever 14 so that it swings in a plane crosswise of the rail, and by constructing the body of the follower as described, practically the whole of the interior of the container may be used for the cards or the like.

What I claim is:

1. A file comprising a base; a rail connected with said base; a follower slidably connected with said rail; a clutch plate of spring metal slidably mounted on the follower and adapted to engage the rail edgewise to lock the follower against movement on the rail, and a cam lever for operating said clutch plate.

2. A file comprising a base; a rail connected with said base; a follower slidably connected with said rail having a body comprising two adjacent walls; a clutch member arranged between the two walls of said follower body and movable toward and

from the rail, and a lever for operating said member, said lever being pivotally mounted between the two follower walls and having its free end extending beyond the latter so as to be used as a handle.

3. A file comprising a base; a rail connected with said base; a follower slidably connected with said rail having a body comprising two adjacent walls; a clutch member arranged between the two walls of said follower body and movable toward and from the rail, and a lever for operating said member; said lever being pivotally mounted between the two follower walls so as to swing up and down in a plane crosswise of the rail and having its free end extending beyond said walls so as to be used as a handle.

4. A file comprising a base; a rail connected with said base; a follower slidably connected with said rail having a sheet metal body comprising two adjacent walls each provided at its lower end with an aperture through which the rail extends, and a lever for locking the follower to the rail, said lever being pivotally mounted between said walls so as to swing up and down in a plane crosswise of the rail and having its free end extending beyond said walls.

5. A file comprising a base; a rail connected with said base; a follower slidably connected with said rail having a sheet metal body comprising two adjacent walls each provided at its lower end with an aperture through which the rail extends, and a wire bail mounted in sockets at the sides of said body; and a lever pivotally mounted on the follower for locking the latter to the rail.

6. A file comprising a base; a rail connected with said base; a follower slidably connected with said rail having a one-piece sheet metal body comprising two adjacent walls each provided at its lower end with an aperture through which the rail extends; a spring clutch plate movably mounted on the follower between said walls and engaging the rail edgewise; a wire bail mounted in sockets at the sides of the body; and a cam lever for operating said plate, said lever being pivotally mounted on the follower between said walls so as to swing up and down in a plane crosswise of the rail, and having its free end extending beyond said walls so as to serve as a handle.

In testimony whereof I have affixed my signature, in presence of two witnesses,

LOUIS AARON LEBOWICH.
